UNITED STATES PATENT OFFICE.

PAUL JOHNSON, OF WINNIPEG, MANITOBA, CANADA.

ELECTRIC COOKER.

1,095,214.

Specification of Letters Patent.

Patented May 5, 1914.

Application filed July 3, 1913. Serial No. 777,243.

To all whom it may concern:

Be it known that I, PAUL JOHNSON, a citizen of the Dominion of Canada, residing in the city of Winnipeg, in the Province of 5 Manitoba and Dominion of Canada, electrician, have invented certain new and useful Improvements in Electric Cookers, of which the following is a specification.

This invention relates particularly to electric cookers which may be carried from place to place and which may be connected by cord to lamp sockets wherever available, to obtain the necessary current.

The objects of my invention have been to 15 provide a device of this character of perfect safety and one in which the intensity of the heat is under control, and which may be produced at a cost much below that of devices of a similar nature now on the market. 20 I attain these objects by the means set out in the specifications and claim following, and fully illustrated in the accompanying drawings in which,

Figure 1 is an elevation of the complete 25 device. Fig. 2 is a sectional view on the line A—B in Fig. 1. Fig. 3 is a circuit diagram showing the connections which may be used in a double or two heat cooker. Fig. 4 is a plan view of the device. Fig. 5 a view 30 of the upper non-conducting ring. Fig. 6 is the grating removed from the heater. Fig. 7 is the lower non-conducting pad with spacing ring and bars. Fig. 8 is a fragment showing the bottom of the device as it 35 might be made to adapt it for use with an ordinary range.

Referring to the drawings in which similar numerals refer to similar parts throughout, it will be observed that in outward appearance the device resembles a shallow circular pan having a handle on one side, connection plugs extending from its opposite side, and legs adapted to support it upon a table or other suitable base.

The casing 1 is made of metal, preferably 45 enameled to insure safety, though this is not absolutely necessary as the construction of the device throughout embodies such precautions as to insulation as make it impossible that the electric current employed could circulate through the case 1 and endanger a person handling it. As mentioned the case 1 may be provided with legs 2, or the bottom may be shaped as shown at 3 in Fig. 8, 50 the part 3 being in size and shape adapted to sit down into the lid opening of the ordinary

coal range, the part 3 maintaining the device in position. By using several of my devices it will be noted that the ordinary range may be in this way, for all practical 60 purposes, transformed into an electric range, and without any change or alteration in the structure of the range itself, the upper part of the case 1 taking the place of the lid openings and being adapted to receive the bottom 65 of pots kettles or pans in the usual way. For use as a portable utensil however, it is better that the device be provided with legs as shown in Figs. 1 and 2. These may be merely porcelain knobs, or they may be of 70 rubber or other material less liable to injure the top of the table or other article of furniture upon which they may rest.

Interiorly disposed upon the bottom of the case 1 is a layer or pad of non-conducting 75 material 4, and immediately above this is a ring 5 of the same material, which rests upon the pad 4 and follows the circumference of the case 1 all around. Crossing the diameter of the interior of the ring 5 and 80 of the same depth or thickness as the same, are spacing bars 6, which, with the ring 5 serve to support in spaced relation to the pad 4, a disk 7 which in cross and circular dimension fits the interior of the case 1. 85 Thus a series of air spaces is formed between the pad 4 and the disk 7. Above and resting upon the disk 7, a ring 8 lines the circumference of the case 1, and supports a circular and removable grating 9. 90

It is preferable that the pad 4, the ring 5, the spacing bars 6, the disk 7, and the lining ring 8 be all of the same heat resisting and non-conducting material, and I have found asbestos board a very suitable material for 95 the purpose.

The pad 4, the ring 5 and the spacing bars 6 are shown as one in Fig. 7, but it will be understood that these may be, and preferably are, separate pieces, and are only 100 brought together as the device is built up.

Secured to the upper side of the disk 7 are the resistance coils 10, 11, 12, 13, 14, 15, 16, and 17, having terminals, 18, 19, and 20 for connection with conducting-wires from 105 which a current of electricity may be obtained to energize the coils. The coils are coreless may be connected up with the terminals and with each other in any manner deemed advisable, that is to say, they may be 110 connected in series to work together as a single unit, or they may be grouped in units

of two or more coils each, controlling means being introduced whereby as many units as are required may be operated together to obtain a desired result. Fig. 3 is a circuit diagram showing the coils divided into two groups, the evenly numbered coils 10, 12, 14, and 16 being connected in series to form one group, and the oddly numbered coils 11, 13, 15, and 17 forming the second group. 5 The pin 18 is the positive terminal of both groups, the pin 19 the negative terminal of the evenly numbered groups, and the pin 20 the negative terminal of the combined group. The conductor cords or wires 21 and 10 22, connect with stationary circuit leads, and pass into a member 23 of insulating material. The member 23 contains three sockets 24, 25, and 26 adapted to receive the terminal pins 18, 19 and 20 respectively, and 15 20 the positive cord 21 connects directly with the socket 24 and thus with the positive terminal 18 of the coils. The cord 22 connects with a switch 27 in the member 23, which may be thrown to connect either with the 25 20 socket 25 thus closing the circuit through the evenly numbered coils, or with the socket 26 which is in contact with the terminal pin 20. As the diagram plainly shows, if the switch 27 be placed to connect the cord 22 with the terminal 19 the current will pass 30 through the coils 10, 12, 14, and 16 generating the amount of heat due to the resistance met with in these coils only, but if the switch be thrown to connect with the terminal 20, 35 the terminal 19 will become a dead end, the current passing from the coil 16 through the wire 28 to the coil 11, thence through the coils 13, 15 and 17 to the terminal 20, thus approximately halving the heating effect of 40 the device. This description illustrates in a simple measure the ease with which the device may be arranged to give off heat of varying intensity, and is not intended to be exhaustive. As it requires a certain amount 45 of force to remove the member 23 from its connection with the terminals 18, 19 and 20, a handle 29 is provided on the opposite side of the casing 1 by which the device may be held while this is being done. 50 It is preferable that the top of the non-conducting ring 8 be kept below the upper edge of the casing 1 thus forming a ledge around the interior of the casing upon which

to rest the grating 9. The grating 9, I prefer to make of woven wire, though various other constructions will suggest themselves, and to have the same fit the casing snugly though in such manner that it may be removed for cleaning purposes without difficulty. The grating may be used directly for 55 toasting purposes, and it is adapted to support a variety of cooking utensils of smaller diameter than that of the case 1. Vessels of larger circumference than that of the case may rest directly upon the upper edge 60 thereof, and cover the same, when there being no escape of the heat great economy 65 must result.

From the foregoing description taken in connection with the accompanying drawings 70 it will be seen that I have devised a cooker combining great convenience with low cost of construction and one which may be handled with perfect safety.

What I claim as my invention is—

A portable electric cooker comprising an open topped cylindrical outer casing having legs and a handle, a heat resisting pad in the bottom of said casing, a heat resisting ring circumferentially disposed in the casing 75 above said pad, and bars disposed in spaced relation upon the upper surface of said pad, and crossing the interior of said ring, a disk equal in diameter to the interior of said casing supported by said ring and 80 bars, and a second ring of outer diameter equal to the interior diameter of said casing disposed above said disk, a cooking grate, said last named ring adapted to maintain the disposition of said disk, pad, bars and 85 first named ring in said casing, and to support on its upper edge said cooking grate, a plurality of coreless heating coils supported by and secured to the upper surface 90 of said disk in parallel spaced relation to each other, and connected in series, the terminals of said coils passing through the side of said casing, and disengageably connecting with a flexible conductor leading to a source of electrical energy.

In testimony whereof I affix my signature in presence of two witnesses.

PAUL JOHNSON.
